[57] CLAIM

The ornamental design for a holder for display signs or
the like, as shown and described.

DESCRIPTION

FIG. 1 is a perspective view of a holder for display signs
or the like showing my new design;

FIG. 2 is a top plan view thereof;

FIG. 3 is a bottom plan view thereof;

FIG. 4 is a front elevational view, with the opposite side
being a mirror image thereof;

FIG. 5 is a left side elevational view, with the right side
being a mirror image thereof.

FIG. 1

FIG. 2**FIG. 3****FIG. 4****FIG. 5**
